Patented Sept. 1, 1914.

UNITED STATES PATENT OFFICE.

ALVA A. LOOMIS, OF EAST AKRON, OHIO.

RAILWAY-TIE.

1,109,001.

Specification of Letters Patent.

Patented Sept. 1, 1914.

Application filed March 28, 1914. Serial No. 827,993.

To all whom it may concern:

Be it known that I, ALVA A. LOOMIS, a citizen of the United States, residing at East Akron, in the county of Summit and State 5 of Ohio, have invented certain new and useful Improvements in Railway-Ties, of which the following is a specification, reference being had to the accompanying drawings.

This invention relates to new and useful 10 improvements in railway ties and more particularly to metallic ties, the object of the invention being to provide a metallic tie wherein the rails are seated in position and securely clamped in place without the usual 15 fish plates and bolts which extend through the rail and the fastening means.

Another object of the invention is to provide a metallic tie having fastening means whereby the same may be used equally as 20 well at the meeting ends of the rails, hold the same securely in position and eliminate the necessity of the removable fastening means now in use.

Another object of the invention is the provision of a metallic tie of the above character which will possess advantages in points of 25 efficiency and durability, is inexpensive of manufacture and at the same time is simple in construction and operation.

With the above and other objects in view, the invention consists in the novel features 30 of construction and the combination and arrangement of parts to be hereinafter more fully described, pointed out in the claims 35 and shown in the accompanying drawings, in which—

Figure 1 is a top plan view illustrating the rail fastener and tie; and Fig. 2 is a side elevation thereof, parts being broken 40 away and illustrated in section.

In the embodiment of my invention, I illustrate cross ties which are preferably U-shaped in cross section and arranged in an inverted position, said cross ties being generally indicated by the numeral 1'. The rails 2' are mounted upon the top of the tie adjacent the ends thereof and are held against lateral movement in one direction by means of the plates 3', the longitudinal 45 edges of which are bent downwardly, as shown at 4' and adapted to engage over the edges of the tie, said plates being securely retained in position by means of the rivets 50

5'. The inner ends of the plates 3' are curved upwardly, as shown at 6' and are 55 adapted to engage over the base flanges of the rails 2' upon the outer sides thereof to retain said rails against lateral movement in one direction.

Pivottally mounted upon the tie 1' are the 60 clamping rods 7', the inner ends of which are offset, as shown at 8'a, thence extended through the spaced openings 9' within the body of the tie and thence arranged in a plane parallel with the body of the rod, 65 whereby to prevent the detachment of the clamping rod with respect to the tie. The engaging ends of the rods are bent upon themselves to form the loops 10' which are adapted to engage over the inner base flanges 70 of the rails 2'. The extreme outer ends extend transversely across the inner ends of the loops 10', as shown at 11' and are removably disposed within the openings 12'a which are formed in the side walls of the tie 75 to retain the loops 10' into clamping engagement with the base flanges of the rails. It will be apparent that the clamping members 7' may be swung outwardly when it is desired to remove the rails from the tie or 80 place them thereon.

While I have shown and described the preferred form of my invention, it will be obvious that various changes in the details of construction and in the proportions may 85 be resorted to for successively carrying my invention into practice, without sacrificing any of the novel features or departing from the scope of the invention, as defined by the appended claims.

What I claim is:—

1. A device of the class described including a U-shaped tie, clamping plates secured to the ends thereof, clamping rods having their inner ends pivotally mounted within 95 the body of the tie and their other ends bent upon themselves to form loops adapted to engage over the inner base flanges of the rails and their extreme ends disposed transversely across the inner ends of said loops, 100 as and for the purpose set forth.

2. A device of the class described including a U-shaped tie member, clamping plates secured to the ends thereof, clamping rods having their inner ends pivotally mounted 105 within the body of the tie and their outer

ends bent upon themselves to form loops adapted for engagement with the base flanges of the rails and having their extreme ends extending inwardly across the inner 5 ends of the loops and adapted for removable engagement within the side walls of the tie, as and for the purpose set forth.

In testimony whereof I hereunto affix my signature in the presence of two witnesses.

ALVA A. LOOMIS.

Witnesses:

O. S. JOHNSON,
CHAS. HIBELL.
